Charles A. Clark
ATTORNEY.

UNITED STATES PATENT OFFICE

JOSEPH E. KENNEDY, OF NEW YORK, N. Y.

SOUNDPROOF BALL MILL

Application filed November 15, 1927. Serial No. 233,408.

My invention relates to sound absorbers and refers more particularly to the method of absorbing sound in mechanisms of various types wherein noisy operation would be objectionable.

The object of my invention is to eliminate noises in mechanisms by covering the mechanism or parts emitting sounds with a sound absorption means.

10 It is well known in the art that coverings have been used for attempting to silence the excessive noises of certain types of machinery but none of them contemplate the use of the specific combination of elements nor the 15 method of employing the same utilized in this particular invention.

It is also well known that attempts have been made to silence machinery but without success and the herein disclosed method of 20 silencing machinery by absorbing the sound is in successful operation and new and novel over the art.

25 This method is shown applied to an air swept tube mill, for the sake of illustration only, as it is obvious that the same basic principle could be applied to almost any noisy device with equally as good results as are obtained in this particular application.

30 My invention consists of the novel construction, arrangement of parts and method of application hereinafter referred to and described, claimed and substantially as illustrated in the accompanying drawings, wherein similar numerals refer to like parts throughout the several views, in which:—

35 Figure 1, is an elevation, partly in section, of an air swept tube mill to which the sound absorber is applied.

40 Figure 2, is an enlarged cross section of Figure 1, taken on lines 2—2 of Figure 1.

45 In Figure 1, the air swept tube mill 1, is comprised of a cylinder 2, held rotatable in the bearings 3 and 4, to which material may be fed through the chute 5, which directs the material into the cylinder 2.

50 Preheated air from any suitable source is supplied to the cylinder 2, by the pipe 6 at the inlet end and to the secondary preheated air from any suitable source is supplied to the device by the pipe 7, at the outlet end

and the product passes out of the mill through the pipe 8.

The cylinder 2, carrying the pulverizing balls 9, is revolved by means of a gear 10, which meshes into a pinion 11, carried by the shaft 12, in the bearings 13 and 14, one end of this shaft 12, being provided with a coupling 15, which is attached to the shaft 16, of the motor 17, and the whole apparatus is supported on the base 18.

To deaden or absorb the sound caused by the operation of this particular device, as shown, the cylinder 2, comprises a metal shell 19, inside of which is a layer of cork 20, and a lining 21.

On the outside of this shell 19, are five different layers of superimposed materials, first, a layer of cellular material 22, preferably of felt, split at 23 and 24, second, a layer of solid material 25, third, a layer of cellular material 26, preferably of felt, fourth, a layer of solid material 29, and fifth, a layer of fabric 30, joined together at 31, which may be coated with paint or similar material to suit requirements.

Thus it is clearly shown that there are two different and distinct cellular bodies separated by a substantially solid body and each of the cellular bodies provides an independent group of dead air spaces whose function is to absorb the sound waves by neutralizing each others vibrations.

Having thus described the preferred embodiment of my invention, I do not wish to limit myself to the exact arrangement of parts or to the application to this specific type of mechanism, as modifications may be made in the arrangement of the parts and in the application to numerous other mechanisms without departing from the spirit of the invention or scope of the claims.

I claim:—

1. A machine for the reduction of materials, with a casing, and lining, having sound producing devices therein, provided with a plurality of layers of porous sound neutralizing material having varying acoustic insulating cells therein, between the casing and the lining.

2. A machine for the reduction of mate-

rials, provided with a casing, having sound producing devices therein, said casing provided with a cover comprised of a plurality of porous sound neutralizing materials, having varying acoustic insulating cells therein.

3. In combination with a revolving drum, of a mill, for the reduction of materials, containing sound producing means, a layer of sound neutralizing material thereupon, having a suitable percentage of porosity, and another layer of sound neutralizing material thereupon having a lesser percentage of porosity.

15 4. In combination with a revolving drum, of a mill, for the reduction of materials, containing sound producing devices, a layer of sound neutralizing material having a suitable percentage of porosity mounted thereon, and a layer of sound neutralizing material having a lesser percentage of porosity mounted thereupon and an outside cover.

20 5. The combination with the revolving drum of a mill for the reduction of materials containing sound producing devices, of a layer of sound deadening and neutralizing materials having a suitable percentage of porosity mounted thereupon, and a layer of sound deadening and neutralizing materials 25 having a lesser percentage of porosity mounted thereupon and an outside cover of fibrous material.

30 6. The combination with the revolving drum of a mill for the reduction of materials having sound producing devices therein, of a layer of sound deadening and neutralizing materials having a suitable percentage of porosity thereupon, a layer of sound deadening and neutralizing materials having a 35 lesser percentage of porosity thereupon and an outside cover of fibrous material having its pores sealed.

40 Signed at New York, in the county and State of New York, this 14th day of November, 1927.

45 JOSEPH E. KENNEDY.
